UNITED STATES PATENT OFFICE.

CHRISTIAN WILLIAM MEINECKE, OF JERSEY CITY, NEW JERSEY.

DESIGN FOR A SYRINGE.

SPECIFICATION forming part of Design No. 31,034, dated June 20, 1899.

Application filed May 25, 1899. Serial No. 718,295. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Nose and Ear Syringe, of which the following is a specification.

The feature of this design consists in a rounded soft-rubber bulb and a curved hard-rubber nozzle having a fluted bulbous tip, as set forth in the following specification and claim and illustrated in the annexed drawing, showing a side elevation of the syringe.

The soft-rubber bulb is shown with its side

in cross-section. The hard-rubber nozzle 3 is curved or might be called of "gooseneck" shape and has a fluted bulbous tip 4.

The design presents a novel, striking, and characteristic appearance.

What I claim as new, and desire to secure by Letters Patent, is—

The design for a syringe substantially as shown and described. 25

In testimony whereof I have hereunto set my hand in the presence of two subscribing witnesses.

CHRISTIAN WILLIAM MEINECKE.
